U.S. Cl. D48—20 R

FIG. 1

FIG. 2

FIG. 3

FIG. 4

FIG. 5

FIG. 1 is a perspective view of a lamp base showing my new design;

FIG. 2 is a front elevational view thereof;

FIG. 3 is a rear elevational view thereof taken substantially perpendicular to the panel of the rear face, the remaining faces being identical thereto;

FIG. 4 is a top plan view thereof; and

FIG. 5 is a bottom view thereof.

The lamp base is shaded to indicate transparency.

The small standard is broken away to indicate indeterminate length.

I claim:

The ornamental design for a lamp base, as shown and described.
